UNITED STATES PATENT OFFICE

119,344

DESIGN FOR A DRESS ENSEMBLE

Louis Katz, New York, N. Y.

Application December 18, 1939, Serial No. 88,972

Term of patent 3½ years

To all whom it may concern:

Be it known that I, Louis Katz, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design;

Fig. 2 is a rear view of Fig. 1;

Fig. 3 is a front view of the dress member of the ensemble shown in Figs. 1 and 2, and

Fig. 4 is the rear view thereof.

The design is characterized by the combination on the hooded jacket portion of the specific dress ensemble disclosed of the specific embroidery arranged on the front of the jacket and continuing around the edge of the hood, as shown.

I claim:

The ornamental design for a dress ensemble, substantially as shown and described.

LOUIS KATZ.
